Application November 17, 1954, Serial No. 33,135

Term of patent 14 years

(Cl. D79—2)

Fig. 1

The memorial plaque is characterized by the particular floral decoration surrounding the vase and those in the corners.

I claim:

The ornamental design for a cemetery memorial plaque or the like, substantially as shown and described.
